5 Claims. (Cl. 261—124)

1

This invention relates to permeable diaphragms for the intimate dispersion of fluids into liquids.

It is known that fine dispersions of fluids in liquids may be produced by a variety of devices such as sintered or porous plates, sparge pipes and the like, bubble cap trays, and mechanical means such as turbo-mixers and other agitating devices, but these means suffer from one or more of the following disadvantages, namely blocking of the fine passages by solid or sticky material, coalescence of the issuing bubbles or globules, production of relatively coarse dispersions when large orifices are used, the necessity for high orifice velocities and consequent high power consumption, wear and tear of moving parts and unsuitability for high pressure or corrosive conditions.

It has now been found that the difficulty associated with blockage of the fine apertures previously used for the dispersal of fluids into liquids by means of permeable diaphragms can greatly be reduced by means of a diaphragm having a multiplicity of apertures provided with closure means, actuated by the pressure differential across the diaphragm, to open progressively with increase in the relative pressure of the fluid to be dispersed.

Accordingly, the present invention relates to a disperser comprising a container fitted with an air or fluid inlet means and covered with a diaphragm which consists of a sheet of a substantially rigid material bearing one or more apertures wherein each aperture is provided with closure means which open or close in response to variations in the pressure differential across the diaphragm. The closure means may preferably be a rectangular flexible flap fixed at one end and operatively biased at the other end to remain closed in the absence of a sufficient differential pressure across the diaphragm and to provide an inherent non-return means by virtue of the overlap of its opposite biased edge with respect to the aperture which it covers. Preferably the diaphragm bears at least 25 such apertures and bears at least one such aperture per square centimetre of diaphragm area. The present invention also relates to a process for the dispersion of fluids in liquids which comprises passing the fluid to be dispersed through a diaphragm as defined above, immersed in the liquid.

The term "aperture" as used in the specification and claims is intended to mean any hole or orifice made in the diaphragm by removal of diaphragm material. It is preferred that the diameter of the apertures is in the range $\frac{1}{16}$ inch

2

to $\frac{1}{4}$ inch. The diaphragm may consist of a rigid plate of a metal such for example as steel, stainless steel, brass, copper, bronze, aluminum and aluminum alloys, or of a non-metallic material such as Bakelite or other plastic materials, inert to the fluids in use.

It is preferred that the closure means should not incorporate any sliding mechanism such as the retaining means of mushroom or similar valves. To prevent the liquid from flowing back to any substantial extent on reversal of the pressure differential, a non-return means may advantageously be incorporated where this is not inherently present. The closure means preferably comprises a flexible flap or strip which overlies the aperture. The flexible flap is suitably made of a metal of a thickness in the range 0.005 inch to 0.025 inch.

The accompanying diagrams illustrate various 20 embodiments of the invention.

Figure 1 is a diagrammatic plan view of a fragment of a diaphragm, and Figure 2 is a cross-section of Figure 1 along line X—X.

Figure 3 is a diagrammatic cross-sectional view 25 of a disperser.

In Figures 1 and 2, the aperture A in the fragment B of the diaphragm is closed by an overlaying strip CDEF of flexible material such as thin steel plate secured to the diaphragm in the region of the edge CF. On supplying fluid under 30 pressure the overlaying strip CDEF lifts slightly to allow a thin stream to pass through and disintegrate into small bubbles or globules in the liquid disposed on the other side of the diaphragm. A number of such apertures and closure means are provided on one diaphragm and should a substantial proportion become blocked by solid matter, the resultant increased back-pressure effects a wider opening of the closure means to allow the solid to pass through whereby 35 the diaphragm is self-cleaning. A non-return means is inherently present by virtue of the overlap of strip CDEF with respect to aperture A.

The process and apparatus of this invention 40 find application generally for the dispersion of a fluid into an incompletely miscible or immiscible liquid to give an intimate contact between the two resulting phases, and may be applied to the aeration of liquids, as in the aeration of fermentation broths, and as in froth flotation processes, in gas washing by passing the gas through a liquid, in the absorption of gases in liquids, in degassing liquids by blowing through an inert gas and in chemical processes involving reacting 45 a gas with a liquid, to vapour liquid contacting,

as in distillation processes for the construction and operation of bubble trays, and to liquid-liquid contacting, as in solvent extraction processes.

The diaphragm is suitably mounted in a disperser comprising a container 10 provided with a fluid inlet 11, said diaphragm forming the fluid outlet of the container, as shown in Figure 3.

I claim:

1. A disperser for the intimate dispersion of fluids into a liquid comprising, a container, a diaphragm mounted on the top of said container, a fluid inlet means for the container, said diaphragm forming the fluid outlet of the container and consisting of a substantially rigid sheet bearing at least one aperture per square centimeter of diaphragm area, each aperture being provided with a rectangular flexible flap which opens and closes in response to variations in the pressure differential across the diaphragm, said flap fixed at one end to the sheet and operatively biased for closure at the other end, and said flap having a cross sectional area substantially greater than that of said aperture to thereby provide an inherent non-return means for the liquid into which said disperser is immersed. 25

2. A disperser as in claim 1 wherein said sheet bears at least 25 apertures.

3. A disperser as in claim 1 wherein said aperture is rectangular and the short and long dimensions thereof are about $\frac{1}{16}$ inch and $\frac{1}{4}$ inch respectively. 30

4. A disperser as in claim 1 wherein said flap is made of metal having a thickness in the range of from about 0.005 inch to about 0.025 inch.

5. In a disperser adapted to be immersed into a liquid for the intimate dispersion of fluids into said liquid, formed of a container, a diaphragm mounted on the top of said container and a fluid inlet means for the container, said diaphragm consisting of a substantially rigid sheet bearing at least one aperture per square centimeter of diaphragm area, each aperture being covered with an overlying rectangular flexible flap which opens and closes in response to the pressure differential across the diaphragm, said flap fixed at one end to said sheet and operatively biased for closure at the other end, and said flap having a cross sectional area substantially greater than that of said aperture to thereby provide an inherent non-return means for the liquid and the outlet means for the fluid which is dispersed into the liquid. 15 20
